UNITED STATES PATENT OFFICE.

OTTO C. BOEGE AND HUGO A. A. BELZ, OF NEW YORK, N. Y.

LOUD SPEAKER.

Application filed April 9, 1924. Serial No. 705,197.

The present invention relates to a loud speaking attachment for telephone receivers, and is more particularly directed toward a device suitable for use with either the permanent magnet type of receiver furnished with telephones, or with the watch-case type of receiver common in head-sets of radio receiving instruments.

The holding of the former type of receiver to the ear of the listener requires the use of the hand and restricts the movement of the listener about the telephone instrument. It is also very tiring on the listener, if the conversation be long continued. The holding of the head-set receivers over the ears is also annoying and unpleasant, and makes it impossible for a number of persons to simultaneously listen in on one head-set.

The present invention contemplates the provision of an attachment suitable for use with telephone receivers so as to make it unnecessary for the listener to apply the receiver or receivers directly to the ears.

It also contemplates a loud speaking attachment to which the receivers may be permanently or temporarily attached as desired, and preferably one having a horn which may be made readily removable and which may be easily oriented as desired.

In the accompanying drawings one of the many possible embodiments of the present invention is shown for purposes of illustration, it being understood the invention may be variously embodied in other forms. In these drawings:

Figure 1 shows a sectional view of the attachment;

Figure 2 shows an elevational view, with parts in section on the line 2-2 of Figure 1.

The form of the attachment shown in the drawings has a base 10 preferably made in two sections 11 and 12 suitably hollowed out as at 13 and 14 so that when assembled as shown there is provided a resonating chamber 15 inside the base. This resonating chamber may conveniently be cylindrical as shown, or may take any other suitable and convenient configuration.

The upper part 11 of the base is provided with an external seat 16 for supporting a telephone receiver. This seat is preferably provided with a circular flange 17 and a conical portion 18 adapted to fit the receiver. It is adapted to hold a watch-case type re-

ceiver 19 as shown in dotted lines in Fig. 1, 55 or an ordinary telephone receiver 20, as shown in dotted lines in Fig. 2. A rounded passage 21 extends inwardly from the receiver seat so as to reach the resonating chamber. It will therefore be apparent that 60 the sound vibrations produced by the receiver diaphragm will be directed into the resonating chamber. In order to utilize these vibrations, a horn 22 preferably having a conical lower end 23 is inserted into 65 a conical hole or passage 24, which extends through the upper part of the base and communicates with the resonating chamber 15. This horn may be readily removed from the base or may be turned in any desired direction in an obvious manner. If desired, however, the horn may be fixed in position in its socket.

While the structure heretofore described is suitable for use with the permanent magnet receiver 20, it is possible to so arrange the attachment that one may use both receivers of a head-set. When making an attachment for this purpose, one provides the lower part 12 of the base with a recess 25 75 adapted to accommodate the watch-case type receiver 26 which is preferably held against an external seat 27 similar to the seat 16 by a leaf spring 28 pivotally mounted on the under side of the base, as at 29. A rounded passage 30, communicating with the resonating chamber, is adapted to convey the vibrations from the receiver 26 into the chamber. When the two receivers 19 and 26 are used, the vibrations reinforce one another in 80 the chamber 15 and the sound is readily heard through the trumpet 22. This structure may be used with a single receiver by resting the receiver on the upper seat 16 and placing a dummy in the recess 25 or otherwise closing the passage 30.

It will thus be apparent that there has been provided a loud-speaking attachment suitable for telephone receivers of various types by the use of which one is relieved of the direct application of a receiver to the ear. Several persons may listen to the sounds issuing from the loud speaker, and the listener may move about as desired.

It is obvious that the invention may be embodied in many forms and constructions, and we wish it to be understood that the particular forms shown are but a few of the

many forms. Various modifications and changes being possible, we do not limit ourselves in any way with respect thereto.

• What is claimed is:

5 1. A loud speaking attachment for telephone receivers, comprising, a base having a resonating chamber, and having an external seat for a telephone receiver associated with a passage extending to the resonating 10 chamber, and an amplifying horn carried by the base and in communication with the resonating chamber.

15 2. A loud speaking attachment for telephone receivers, comprising, a base having a resonating chamber, and having a pair of external seats for telephone receivers, each associated with a passage extending to the resonating chamber, and an amplifying horn carried by the base and in communication 20 with the resonating chamber.

25 3. A loud speaking attachment for telephone receivers, comprising, a base having a sound transmitting opening therein, and having a pair of external seats for telephone

30 receivers, each associated with a passage extending to the sound transmitting opening, one of said seats being provided with a device for clamping a receiver in place and the other constructed to permit a receiver to be placed in or removed from it without obstruction, and an amplifying horn carried by the base and in communication with the sound transmitting opening.

35 4. A loud speaking attachment for telephone receivers, comprising, a base having a resonating chamber, and having a pair of external seats for telephone receivers, each associated with a passage extending to the resonating chamber, one of said seats being 40 in a recess adapted to accommodate the receiver, and an amplifying horn carried by the base and in communication with the resonating chamber.

45 5. A loud speaking attachment for telephone receivers, comprising, a base having a sound transmitting passage therein, and having an external seat for a telephone receiver associated with a passage extending to the sound transmitting passage, and an 50 amplifying horn carried by the base and in communication with the sound transmitting passage, the lower end of the horn being conical and removably fitted into a conical hole in the top of the base.

6. A loud speaking attachment for telephone receivers, comprising, a base having an upper section and a lower section, said sections enclosing a resonating chamber, one of said sections being provided with an external seat for a telephone receiver associated with a passage extending to the resonating chamber and an amplifying horn removably carried by the upper section of the base and in communication with the resonating chamber. 55

7. A loud speaking attachment for telephone receivers, comprising, a base having an upper section and a lower section, said sections enclosing a resonating chamber, one of said sections being provided with an external seat for a telephone receiver associated with a passage extending to the resonating chamber, and an amplifying horn removably carried by the upper section of the base and in communication with the resonating chamber, the lower end of the horn being conical and fitted into a conical hole in the upper section of the base. 60 70

8. A loud speaking attachment for telephone receivers, comprising, a base having an upper section and a lower section, said sections enclosing a resonating chamber, each of said sections being provided with an external seat for a telephone receiver associated with a passage extending to the resonating chamber, the lower section being provided with a device for clamping the receiver in place, and an amplifying horn removably carried by the upper section of the base and in communication with the resonating chamber. 80 85

9. A loud speaking attachment for telephone receivers, comprising, a base having an upper section and a lower section, said sections enclosing a resonating chamber, the lower of said sections being provided with an external seat for a telephone receiver associated with a passage extending to the resonating chamber, said seat being in a recess adapted to accommodate the receiver, and an amplifying horn removably carried by the upper section of the base and in communication with the resonating chamber. 90 95

In testimony whereof we have affixed our signatures to this specification.

OTTO C. BOEGE.
HUGO A. A. BELZ.
